UNITED STATES PATENT OFFICE.

THOMAS A. WATSON, OF BOSTON, MASSACHUSETTS.

TELEPHONE.

SPECIFICATION forming part of Letters Patent No. 245,105, dated August 2, 1881.

Application filed April 25, 1878.

To all whom it may concern:

Be it known that I, THOMAS A. WATSON, of Boston, Massachusetts, have invented a new and useful Improvement in Telephones, which 5 improvement is fully set forth in the following specification.

This invention relates to telephones or telephonic transmitters in which undulatory currents are produced in a battery-circuit by the 10 variations of pressure between electrodes, which variations in pressure create corresponding variations in the resistance of the circuit, and consequently in the tension of the current on said circuit. These variations in pressure 15 are caused by the vibration of a diaphragm or elastic plate. One of the electrodes is usually carbon.

The present invention has for its object to 20 secure increased efficiency in the conversion of sound-waves into electric undulations; and to this end it consists in the construction and combination of parts as hereinafter more fully set forth, whereby the diaphragm is allowed to vibrate freely under the action of the sound- 25 waves, and a more perfect contact between the electrodes and a better transmission of pressure to them from the diaphragm are at the same time secured.

In the accompanying drawings, which form 30 a part of this specification, Figure 1 is a sectional view of a telephone embodying the invention, and Fig. 2 a diagram illustrating the manner in which such an instrument is or may be connected in circuit for use with a receiving- 35 telephone.

In Fig. 1, A is a mouth-piece for conveying the sound-waves to the vibratory plate or diaphragm B, which is formed of a thin sheet of metal in the usual way. To the center of this 40 diaphragm is rigidly secured a metallic piece or electrode, E, which makes contact with a carbon disk or electrode, C. This metallic piece has a small surface in contact with the diaphragm, so as to interfere as little as may 45 be with the vibration of the latter, while a larger surface is preferably in contact with the carbon electrode.

By having as the carbon electrode C a disk 50 a larger surface can be brought into contact with the metallic electrode than if a carbon point were used, thus producing better results

by diminishing the resistance offered to the passage of the electric current from one electrode to the other, and at the same time diminishing the liability of the two electrodes 55 to break or become separated, so as to interrupt the current.

As shown, the carbon button or disk is hollowed to receive the rigid metallic piece or electrode.

At the back of the instrument is a support, F, having a threaded opening for the set-screw D. This screw is fitted to or bears at the inner end against the carbon button or electrode and serves to regulate the pressure of the same 60 upon the metallic electrode or rigid piece, which is interposed between it and the diaphragm B. It will be seen, therefore, that words or other sounds uttered into the mouth-piece A will communicate vibration to the diaphragm 65 B, and will vary the pressure between the electrodes E C, and will increase or diminish the current flowing over a battery-circuit including the electrodes.

The circuit is completed by connecting the 70 opposite poles of a battery by suitable conductors with the binding-posts G H. The post G is carried by the support F, which, as shown, is a rigid support of metal. The post H is electrically connected with the diaphragm, and 75 the circuit passes from one post to the other through the diaphragm, metallic connecting-piece E, or metallic electrode, carbon electrode C, screw D, and support F.

In Fig. 2 the telephone-receiver A' is shown 80 included in the secondary circuit b of an induction-coil, B', and the transmitter C' and battery D' included in the primary circuit a of the same. This figure is only intended to illustrate the manner of connecting the instruments in circuit, the particular construction of 85 the transmitter constituting the present invention not being illustrated.

The connection of a carbon-telephone with a receiver and induction-coil, as shown, constitutes no part of the present invention.

Having thus fully described the said invention and the manner of carrying the same into effect, what I claim, and desire to secure by Letters Patent, is—

1. The combination, with a telephone diaphragm or vibratory plate, of an electrode at-

tached at the center of said plate or diaphragm, and having a small area in contact therewith, so as to interfere as little as possible with the vibration of the plate or diaphragm, substantially as described.

2. A telephone-transmitter comprising a vibratory diaphragm, an electrode connected with the diaphragm so as to partake of its vibration, and having a small area in contact therewith, and a second electrode in electrical contact with the vibratory electrode, substantially as described.

3. The combination of a diaphragm, a carbon button or disk forming an electrode, an electrode connected with the diaphragm so as to partake of its vibrations, and interposed

between it and the carbon button or disk, and means, as indicated, for adjusting the pressure between the electrodes, substantially as described.

4. The combination of the rigidly-supported and adjustable button or disk, the diaphragm, and the interposed metallic connection attached to said diaphragm so as to vibrate with it, substantially as described.

In testimony whereof I have signed this specification in the presence of two subscribing witnesses.

T. A. WATSON.
